UNITED STATES PATENT OFFICE.

WILLIAM JOHN, OF MORRISTON, SWANSEA, WALES.

FURNACE FOR ANNEALING METAL PLATES.

1,310,911.

Specification of Letters Patent.

Patented July 22, 1919.

Application filed April 15, 1919. Serial No. 290,298.

To all whom it may concern:

Be it known that I, WILLIAM JOHN, a subject of the King of Great Britain, residing at Morriston, in the borough of Swansea, 5 South Wales, have invented certain new and useful Improvements in and Relating to Furnaces for Annealing Metal Plates, of which the following is a specification.

This invention relates to the construction 10 of furnaces of the kind which are used for annealing metal, more especially rolled iron plates preparatory to being tinned or plated.

A furnace of this kind, as hitherto constructed, usually has a fire-place or fire- 15 places at one end, reinforced in some cases with fire places in the sides, and a doorway for admitting and withdrawing the plates at one end, the smoke and heat from the fire passing through the furnace into the 20 flues and up through the stack or chimney to the open air. The plates to be treated are covered with an iron casing and run into the furnaces on a trolley. They are subjected to the heat for about 8 or 9 hours to 25 complete the annealing process, and are then withdrawn. During this process, a large percentage of the heat passes with half-burnt gases ineffectively around the plates and is wasted.

30 The main object of my invention is to conserve the heat, reinforce it where required, and apply it in the most effective way to secure the desired results.

With these objects in view, I propose to 35 build the furnace on a substantially tapered plan, the door-way for admission of the trolleys being at the smaller end, another for their discharge at the larger end, and fireplaces, one on each side of the discharging door, the purpose being to distribute 40 the heat evenly on both sides and to concentrate the heated streams of air and gas and prevent their being unduly dissipated and cooled before reaching the smaller end. For 45 the same purpose and to increase the heat and combustion where most wanted, I propose to provide additional fire places and other improvements.

These will be best described with reference 50 to the accompanying drawings, showing a furnace constructed in accordance with my invention.

In these, Figure 1 is a central longitudinal section of the furnace, Fig. 2 a plan of 55 the same in two sections, the upper half on

line 2^x and the lower half on line 2^y of Fig. 1, the tracks E being omitted.

Fig. 3 is a section on line 3^x of Fig. 2.

Fig. 4 is a section on line 4^x of Fig. 2.

Fig. 5 is a section on line 5^x of Fig. 2.

All views of the drawings, excepting Fig. 1, omit the stands, trucks or trolleys F.

In the front wall at the end of the furnace, where the tapering side walls A are at their greatest distance apart, I provide the 60 two fireplaces C C for coal, with stokeholes C¹ one on each side of a central opening for discharge of the trolleys.

About midway of the length of the furnace in the side walls I provide two additional fire places D D for burning coke with stokeholes D¹. These are so placed that the heated gases and smoke from the coal fireplaces C, after passing over the bridges C¹, are made to pass over the coke fires where 70 they become ignited and, passing over the bridges D¹, intensify the heat in the first portion R of the furnace through which they pass on their way to the flues S through which they pass to discharge flue T. The 75 walls at the sides of the bridges C¹ and the parts D¹ of the casings of the coke fireplaces are extended upward to the roof M as partitions across the furnace, openings covered by drop doors K and L being left 80 in them to allow the trolleys or trucks F to pass from end to end. Similar drop doors B and J are provided at the admission and discharge openings respectively. These 85 doors are arranged to work in vertical slots 90 and to be balanced by weights with chains passing over pulleys (not shown). The purpose of these partitions and doors is to insure that the streams of heated gases shall 95 pass along the sides of the furnace and over the coke fires before reaching the flues at the narrow end.

The flues S communicate with flue T which discharges into the stack U on the raising of a damper W, and also communicate with culverts Y at points S' under the floor which pass below the coke and coal fire places and discharge into the spaces above the fires in the latter. Fans X, rotatable from the outside are mounted in the 100 culverts Y for the purpose of drawing the hot gases and smoke through the flues S and flue T and driving them back to the coal fires to mingle with the new gases and undergo more complete combustion.

Right through the length of the furnace a central runway or track E is provided along which the iron trolleys or trucks F on which the plates are stacked can run. These trolleys or trucks travel on ball bearings situated in parallel grooves in the runway in a known manner, the bottom of each trolley or truck being correspondingly grooved.

The charge stands F, see Fig. 1, are inserted successively at the door B and impelled toward the discharge end where they are removed through the door J, a fresh one being inserted as a used one is removed, the latter being then unloaded and brought around to repeat the journey with a fresh load. Each load of plates is thus subjected to a gradually increasing heat to a maximum degree near the coke fires in the first chamber R, where the waste gases become incandescent, and is passed on to the annealing chamber N, thence to the "soaking" chamber P beyond the furnace fires, and is finally discharged. A small chimney Z is provided in the roof of the chamber P.

Each stand or truck or trolley F may conveniently carry four stacks of plates (not shown) and the whole runway may accommodate about four stands within the furnace. Of these, two may occupy the space R between the admission door B and the coke fire places D, one may occupy the chamber N and one may occupy the chamber P, and beyond the furnace fires at the end of P is the door J for the discharge of the trolleys.

The stack U will be used only when the fires are set going. When the furnace attains its proper heat the damper W will be closed, and the heated gases and smoke will be driven along the culverts Y as described to pass again over the coal fire-places C. Steam blowers may also be fixed under the fire places to drive the heated air, etc., toward the narrow end of the furnace and assist the fan X in insuring a continuous circulating current as indicated by arrows in Fig. 3. When the furnace becomes overfull

of heated air and gases, these will be forced back to the soaking compartment P and be discharged through a small chimney Z. The condition of the pots may be watched through sight holes V.

It will be understood that I do not limit my invention to the precise numbers of stands, pots, chambers or fire-places or proportions mentioned or shown in this description.

I claim:

1. A furnace for annealing metal plates, a central track along the same for trolleys, a drop door at the receiving end and a similar door at the discharge end, the side walls of the furnace being tapered so that it is wider at the discharge end than at the receiving end, two fireplaces for coal at the wider end, one at each side of the discharge door, and two additional fireplaces for coke, one in each of the taper side walls near the middle of the furnace.

2. A furnace for annealing metal plates, a central track along the same for trolleys, a drop door at the receiving end and a similar door at the discharge end, the side walls of the furnace being tapered so that it is wider at the discharge end than at the receiving end, two fireplaces for coal at the wider end, one at each side of the discharge door, two additional fireplaces for coke, one in each of the taper side walls near the middle of the furnace, and two transverse partitions dividing the furnace into three chambers, drop doors in such partitions, also a culvert or culverts for returning the gases for re-consumption, together with means for propelling and means for regulating the flow of said gases.

In testimony whereof, I have signed my name to this specification in the presence of two subscribing witnesses.

WILLIAM JOHN.

Witnesses:

IVOR JOHN,
KATHLEEN POOLE.
